UNITED STATES PATENT OFFICE.

ROBERT KELLER, OF DETROIT, MICHIGAN.

DESIGN FOR AN INK-WELL

40,777.

Specification for Design.

Patented July 19, 1910.

Application filed May 19, 1910. Serial No. 562,346. Term of patent 3½ years.

To all whom it may concern:

Be it known that I, ROBERT KELLER, a citizen of the United States of America, residing at Detroit, in the county of Wayne and State of Michigan, have invented a new, original, and ornamental Design for Ink-Wells, of which the following is a specification, reference being had therein to the accompanying drawings.

Figure 1 is a perspective view of an ink-

well showing my new design, Fig. 2 is a side elevation thereof.

I claim:—

The ornamental design for an ink-well as shown.

ROBERT KELLER.
